UNITED STATES PATENT OFFICE.

EDWIN L. GAGE, OF TOLEDO, OHIO.

COLLAPSIBLE DRUM FOR VENEER-PACKAGE MACHINES.

No. 905,305.

Specification of Letters Patent.

Patented Dec. 1, 1908.

Application filed January 11, 1908. Serial No. 410,823.

To all whom it may concern:

Be it known that I, EDWIN L. GAGE, a citizen of the United States, and a resident of Toledo, in the county of Lucas and State of Ohio, have invented a certain new and useful Collapsible Drum for Veneer-Package Machines; and I do hereby declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to package forming machines, and particularly to the class of such machines in which veneering or other like material is shaped in cylindrical form about a forming drum or mandrel.

The primary object of my invention is the provision in a machine of this class of an improved form of forming drum or mandrel, the segments of which are each mounted for contractual or collapsible movements relative to the drum axis, whereby circumferential grooves in the drum in which the internal hoops or strengthening means of the barrel or package seat are drawn inwardly free from such hoops or means to permit an easy and unrestricted withdrawal of the formed article from the drum.

The operation, construction and arrangement of the parts of the invention are fully described in the following specification and illustrated in the accompanying drawings, in which,—

Figure 1 is a front elevation of a machine embodying the features of my invention with one end portion of the forming drum in section. Fig. 2 is an enlarged cross-section of the drum on the dotted line α α in Fig. 1, and Fig. 3 is a similar section with the parts shown in collapsed position.

Referring to the drawings, 1 designates the drum-shaft, which is shown as having one end journaled in the two bearing-stands 2, 2 and its other supported in a bearing-gate 3, which is hinged in a suitable manner to one of the standards 4 of the machine. The standards 4 are disposed a suitable distance to the rear of the shaft 1 to permit an endwise removal of the formed article from the shaft-drum when the gate 3 is swung outwardly for such purpose.

Mounted on the shaft 1 between the gate 3 and inner standard 2 is the collapsible

forming-drum or mandrel 5, the shell of which is composed of a plurality of segmental sections 6, which, when lying with their side edges abutting, are intended to form a true cylindrical surface, as shown in Figs. 1 and 2. Projecting inwardly from the end of each section 6 is an arm or spoke member 7, which is pivoted at its inner end, as at 8, to the outer end of one of the arms 9 projecting radially from a collar 10, which is mounted on the shaft 1, thus providing a form of toggle connection between the collar and each drum section. The arms 7 are preferably disposed in tangential relation to the shaft 1 so as to extend laterally from their point of connection with the arms 9 as shown.

Interposed between the two end collars 10 of the drum on the shaft 1 therewith is a sleeve 11 which has its ends abutting against said collars and provided with radial arms 12. These arms correspond in number to the drum segments and are provided at their ends with lateral studs 13, which work in cam slots 14 provided longitudinally in the contiguous segment arms 7 adjacent their outer ends, as shown. It is thus apparent that a relative turning in one direction of the collars 10 and sleeve 11 when the segments are in expanded or set-up position, as in Fig. 2, will cause the studs 13 to move outwardly in their respective slots 14 and effect a simultaneous and uniform collapsing or contractual movement of all of the segments relative to the drum axis due to the segments oscillating in the same direction on their pivots 8; and that a relative turning in the other direction of said sleeve and collars when the parts are in collapsed position, as in Fig. 3, will cause the studs 13 to move inwardly in their respective slots and effect a simultaneous and uniform outward movement of the segments on their pivots to set-up position. In order to reduce the frictional resistance between the studs 13 and slots 14 when the collars 10 and sleeve 11 are relatively turned, the arms 12 are curved in the same direction in which the attached segment-arms 7 extend from the arms 9 of their collars so that the arms 12 and the respective slots 14 in which they work stand in substantial longitudinal alinement.

The parts of the drum are locked in set-up or expanded position by threading an arm-nut 15 to an extended end of one of the studs 13 of the arms 12, thus adapting a tightening

movement of the nut to clamp the associated arms 7 and 12 together, or this locking may be accomplished in any other suitable or convenient manner. The arm-nut 15 also serves 5 as a handle which the operator can grasp and turn with the associated arm 12 and its sleeve when it is desired to impart relative rotation to the collars 10 and said sleeve for the purpose of collapsing or expanding the 10 drum parts. For this reason the sleeve 11 is shown as being loose and the collars 10 fixed to the shaft. As the swinging movement of the segments when being collapsed causes the forward edge of each to work within and 15 past the rear edge of the next section, as shown in Fig. 3, the abutting edges of the segments are oppositely beveled in a manner to permit of such movement, as shown at 16.

To adapt the drum for the forming of 20 barrels or like packages having internal hoops or strengthening pieces, it is provided with a desired number of circumferential grooves 17 in which the hoops or strengthening pieces may lie during the forming 25 process as hereinafter described.

Power is communicated to the drum-shaft by a belt engaging the pulley 18 on the shaft 19, which has one end journaled in a pivotal-bearing carried by one of the standards 2, 30 and its other end carrying a friction-wheel 20 for coaction with the friction wheel 21 to transmit rotation to the shaft 22, which in turn transmit rotation to the drum-shaft through the medium of the spur-gears 23. 35 The friction-wheels 20 is thrown into engagement with its companion by a lowering of the foot-treadle 24, which is fulcrumed to the frame base, as at 25, and has its short arm connected to the shaft 19 in a suitable 40 manner to effect a raising of the wheel 20 when the other end of the treadle is lowered.

The pressure-roller 26, which holds the veneering to the drum as it is being wound thereon, has its ends connected to the cross-head 27, by which it is carried and which is mounted for vertical movement in suitable guides in the members 4, 4. To facilitate a raising of the roller 26 from engagement with the drum, a link 28 connects the cross-head with an overhead lever 29, which is fulcrumed to the frame top in a suitable manner and has its handle end adapted to engage a toothed arm 30 on the frame to retain it in adjusted position. 31 designates the usual 50 guides through which the outer hoops of a double veneer barrel or package pass as they wind on the drum with the veneering.

In the making of double veneer-packages, the internal hoops are fed to the grooves 17 60 of the drum and the layers of veneering are fed between the drum and the pressure-roller 26, and their forward ends secured to the drum by being clamped between the abutting edges of two segmental sections 6 of the drum, or secured thereto in any other suit-

able manner. Should external hoops be also used they are passed through the guides 31 and between the pressure-roller and layers of veneering in the same manner as in the machines heretofore employed for such purpose. While the veneering and strengthening hoops are being fed the drum will be caused to slowly revolve by a downward pressure on the treadle 24 to throw the wheels 20 and 21 into frictional engagement. 75 As soon as a sufficient length of veneering has passed the pressure-roller 26 the treadle 24 is released and the drum stops. The meeting ends of the veneering and hoops are now secured together in a suitable manner 80 and the barrel or other package is ready to be removed from the drum. To accomplish this, the gate 3 is swung free from the shaft end, the arm-nut 15 turned to release the clamping action of the associated segment 85 and sleeve arms 7 and 12, and the sleeve 11 and its arms then thrown in the proper direction relative to the shaft to cause the studs 13 to move outwardly in their respective slots 14 and effect a sufficient contractual or 90 collapsing movement of all of the drum segments to withdraw the grooves 17 from engagement with the internal hoops of the formed article, thus permitting the article to be freely withdrawn from the drum 95 lengthwise thereof.

I wish it understood that I do not desire to be restricted to the exact details of construction or arrangement of the parts shown and described, as obvious modifications will 100 occur to persons skilled in the art.

Having thus described my invention, what I claim as new and desire to secure by Letters Patent, is,--

1. In a machine of the class described, a 105 shaft, a forming drum carried by the shaft and having its shell circumferentially grooved and composed of a plurality of segmental sections, and mechanism for effecting uniform oscillatory movements to the several sections to collapse each relative to the shaft, the movements of the sections being in tangential arcs.

2. In a machine of the class described, a 110 drum or mandrel having its shell composed of a plurality of segmental sections, and mechanism for effecting tangentially oscillatory movements of the segments relative to the drum shaft to collapse the drum.

3. In a machine of the class described, a 115 forming drum or mandrel having its shell composed of a plurality of abutting segmental sections, and mechanism for effecting uniform oscillatory movements of the several drum sections to collapse or expand the same the arcs of movement of each section being eccentric to the drum axis.

4. A collapsible drum having its shell composed of a plurality of oscillatory segmental sections, and mechanism for moving the sec- 120

tions relative to the drum axis to cause an edge of each to pass within the contiguous edge of the next section whereby a collapse of the drum is effected.

5. A collapsible drum comprising a shaft, a plurality of segmental rim-sections having inwardly projecting arms, means carried by the shaft to which said arms are pivoted, and a member having arms in sliding engagement with the arms of the rim-sections to adapt a relative movement of said means and member to effect oscillatory collapsing or expanding movements of the several rim-sections.

15. A collapsible drum comprising a plurality of segmental rim-sections having inwardly projected longitudinally slotted arms, means within the sections to which said arms are hinged, and a member within the sections having parts working in said arm-slots to effect oscillatory collapsing or expanding movements of the rim-sections when said means and member have relative rotary movements.

25. A collapsible drum comprising a plurality of segmental rim-sections, a central member in separate toggle connection with each rim-section, and means carried centrally of the drum and coöperating with the several rim-sections to contract or expand the same relative to the drum axis when said member and means have relative rotary movements.

35. In combination, a shaft, a drum carried by the shaft and comprising a plurality of segmental rim-sections having arms projecting inwardly tangential to its axis, collars carried by the shaft and having radial arms to which the rim-section arms are pivoted,

40. a sleeve carried by the shaft and having arms

projecting therefrom and in sliding connection at their ends with the arms of the rim-sections, whereby a relative rotary movement of the collars and sleeve effects simultaneous oscillatory movements of the rim-sections, 45 and means for locking the parts in set-up position.

9. A collapsible drum having a plurality of abutting segmental rim-sections provided with inwardly-projecting arms, the abutting 50 edges of said sections being oppositely beveled, internal means to which the section-arms are hinged, and a rotary member co-operating with the section-arms and movable to effect uniform oscillatory movements of 55 the several sections.

10. In combination, a shaft, armed collars carried by the shaft, arms hinged to and projecting laterally from the collar-arms and having their outer ends terminating in segmental sections adapted to combine to form the rim of a drum, said arms also being provided with longitudinally-disposed slots, a member carried by the shaft intermediate 60 said collars and having arms projecting therefrom and provided at their ends with studs which work in the slots in said arms whereby a relative rotary movement of the collars and member effects either contracting or expanding movements of the several segmental 70 sections, and means for locking the parts in set-up or expanded position.

In testimony whereof I have hereunto signed my name to this specification in the presence of two subscribing witnesses.

EDWIN L. GAGE.
